CLAIM

The ornamental design for a bottle, as shown and described.

DESCRIPTION

FIG. 1 is a perspective view of a bottle showing my new design;

FIG. 2 is a front view thereof, the rear view being the same; FIG. 3 is a right side thereof, the left side view being the same;

FIG. 4 is a top view thereof; and,

FIG. 5 is a bottom view thereof.

The inside of the bottle visible in FIGS. 1 & 4 is not included in the claimed design. The broken lines in the drawings illustrate the portions of the bottle that form no part of the claim.
